UNITED STATES PATENT OFFICE.

DONALD R. MACBAIN, OF CLEVELAND, OHIO.

FREIGHT-CAR LADDER.

1,063,048.

Specification of Letters Patent. Patented May 27, 1913.

Application filed August 22, 1911. Serial No. 445,829.

To all whom it may concern:

Be it known that I, DONALD R. MACBAIN, of Cleveland, in the county of Cuyahoga and State of Ohio, have invented a certain new and useful Improvement in Freight-Car Ladders, of which improvement the following is a specification.

The recent rules of the Interstate Commerce Commission prohibit the operation of freight cars on which a ladder is in any manner defective, and compliance therewith necessitates that the outside ladders, used by the brakemen in going to and from the car roofs, shall be readily and quickly removable when found to be in defective condition. This cannot be accomplished with ladders of the existing constructions, in which the complete ladder, or the individual rungs, as the case may be, are bolted or riveted to the framing or sheathing of the car, and consequently the car must be opened, and in many cases, a portion of the load be shifted, in order to remove and replace a defective ladder or rung.

25 The object of my invention is to provide a freight car ladder of simple, strong, and inexpensive construction, which can be expeditiously attached to and detached from the outside of a car, and be securely held in position when in service.

The improvement claimed is hereinafter fully set forth.

In the accompanying drawings: Figure 1 is a side view, in elevation, of a portion of a freight car body, at and adjoining one end thereof, illustrating an application of my invention; Fig. 2, a partial end view of the same; Fig. 3, a plan view, on an enlarged scale, of the top supporting bracket; Fig. 4, 40 a similar view of the bottom supporting bracket; Fig. 4^a, a front view of the same; and, Figs. 5 and 6, views similar to Figs. 1 and 2, respectively, illustrating a modification of structural detail.

45 In the practice of my invention, I provide a metallic ladder composed of two stile bars, 1, 1, connected at a suitable distance apart, by a plurality of rungs, 1^a, the ends of which are riveted or bolted to the stile bars. In 50 the practice of some railroads, the ladders are attached to the sides of the cars, adjoining one end; in that of others, to the ends, adjoining one side; and, in many cases, to both a side and end of the car, as is illustrated in the instance exemplified. As 55 shown in Figs. 1 and 2, the width dimensions

of the stile bars, 1, are perpendicular to the side and end of the car, except at and adjoining their upper ends, where said bars are bent at right angles so that their width 60 dimensions stand parallel with the side and end, and are bent downwardly into hooks, 1^b.

A top supporting bracket, 2, (one for each ladder), is secured, as a permanent fixture, to the side plate, 3, or end plate, 4, of the 65 car frame, as the case may be, by bolts, 5, and nuts, 5^a. The bracket, 2, is a flat metal plate constituting a spacing member, the ends of which are bent into the form of eyes, 2^a, located at such distance apart as to enable the hooks, 1^b, of the stile bars of the ladder, to be engaged with, or disengaged from them, by vertical movements of the ladder. A bottom supporting bracket constituting a spacing member, 6, (one for each 75 ladder), in the form of a flat metal plate, having its ends turned into loops or sockets, 6^a, adapted to receive the lower ends of the stile bars, is secured as a permanent fixture, to a side sill or end sill of the car frame, as 80 the case may be, by bolts, 7, and nuts, 7^a. The ends of the stile bars, 1, of the ladder, fit in the loops, 6^a, of the bottom bracket, and, in the instance shown, are secured detachably to said bracket, when the hooks, 85 1^b, of the stile bars are engaged with the eyes of the top supporting bracket, by bolts, 8, and nuts, 8^a. It is not, however, essential that the stiles should be secured to the bottom supporting bracket, and any construction of the latter by which they would be engaged therewith and prevented from displacement therefrom, would be within the 90 spirit and scope of my invention.

The ladders shown in Figs. 5 and 6 accord, 95 in all substantial particulars, with that above described, differing therefrom only in that the width dimensions of the stile bars stand parallel with the side or end of the car, instead of perpendicular thereto, the loops of the bottom supporting bracket being, of course, correspondingly changed in position to receive them. In order to prevent the swaying of the ladder toward and from the side or end of the car, the stile bars may, 105 if desired, abut on, or be connected intermediate their ends to, seats, 9, secured to the car framing or sheathing.

It will be seen that the construction of the ladders is simple and such as to combine 110 lightness with strength; that it is securely held in position when attached to the car;

and that its removal and replacement, whenever required, may be effected with ease and quickness and without involving the necessity of access to the interior of the car as heretofore.

5 The brackets 2 and 6 constitute permanent spacing members for the ends of the ladder stiles and are manufactured of standard size so that they may be distributed throughout 10 a railroad system at all repair points. The fact that they are standard eliminates the necessity of the repairman measuring the distance between the eyes in securing them to a car in order that they may be a proper 15 distance apart to receive the stiles of a standard ladder, as this distance is determined when the brackets are manufactured. Thus all that the repairman need do is to fasten the brackets to the car and this he is 20 enabled to do quickly and without measurement, the spacing member of the bracket taking care of the distance between the eyes. I claim as my invention, and desire to secure by Letters Patent:

25 1. The combination with a railroad car, of an upper supporting bracket secured to the outside of the car body and forming eyes adjacent to its ends, a lower supporting bracket secured to the outside of the car

body adjacent its bottom, the ends of which 30 are rebent to form loops spaced from and opening toward the car body, and a ladder comprising stiles the upper ends of which are constructed to engage the eyes of the upper supporting bracket and having lower 35 ends constructed to fit in the loops of the lower supporting bracket, and a plurality of rungs connected at their ends to said stiles.

2. The combination with a railroad car, 40 of an upper supporting bracket secured to the outside of the car body and having eyes adjacent to its ends, a lower supporting bracket secured to the outside of the car body adjacent to its bottom, the ends of 45 which are rebent in the same direction to form loops opening toward the car body, and a ladder comprising stiles having hooks on their upper ends engaging the eyes of the upper supporting brackets and fitting in 50 the loops of a lower supporting bracket, and a plurality of rungs connected at their ends to said stiles.

DONALD R. MACBAIN.
